PIPE WRAPPING MACHINE

Leland S. Rosener and Emil Birk, San Francisco, Calif., assignors to The Paraffine Companies, Inc., San Francisco, Calif., a corporation of Delaware

Application August 26, 1926, Serial No. 131,568

4 Claims. (Cl. 242—11)

Our invention relates to a machine for wrapping a protective strip about a pipe.

One of the objects of the invention is to provide a machine of this character adapted to wrap 5 pipe which has already been laid and is in fixed position in the ground.

Another object of the invention is the provision of a pipe wrapping machine in which a protective strip is wrapped about a fixed pipe 10 and embodying means for applying an adhesive and waterproof fluid to the pipe and wrapping strip to hold the latter in place and seal the pipe within an impervious covering.

Other objects of the invention will be set forth 15 in the following description of the preferred embodiment of our invention which is illustrated in the drawings accompanying and forming part of the specification. It is understood that we do not limit ourselves to the showing made by the 20 said description and drawings as we may adopt variations of our preferred embodiment within the scope of our invention as set forth in the claims.

Referring to the drawings:

25 Figure 1 is a plan view showing the wrapping machine of our invention operating on a pipe line.

Figure 2 is a side elevation of the machine, a portion of the structure being shown in section.

30 Figure 3 is an end elevation, the direction of the view being indicated by the arrow 3 in Figure 2.

Figure 4 is a vertical sectional view thru a modified form of a portion of the machine.

35 Figure 5 is a detail partly in section showing the construction of the spool, the plane in which the view is taken being indicated by the line 5—5 of Figure 4.

Figure 6 is a detail showing the construction 40 of the barrel, the direction of the view being indicated by the arrow 6 in Figure 4.

In broadly descriptive terms, the wrapping machine of our invention comprises a frame provided with wheels for supporting it upon the pipe to be wrapped. A hollow spool on which a quantity of the wrapping material is held is journaled on the frame about the pipe and a wrapping arm for applying the wrapping material from the spool to the pipe is mounted on the frame for orbital rotation about the pipe. Means are provided for causing rotation of the wrapping arm to wind the wrapping strip about the pipe and simultaneously rotating one of the supporting wheels to advance the frame carrying the arm axially along the pipe so that the

resulting movements of the wrapping arm wraps the strip about the pipe spirally. Means are also provided for applying a fluid such as hot asphalt between the pipe and the wrapping material, so that the wrapping strip is adhesively retained in place and the laps sealed with a waterproof, decay resisting and durable material.

More particularly, our wrapping machine comprises a frame 2, on which is journaled a shaft 3, carrying a knurled wheel 4, adapted to support one end of the frame upon the pipe or pipe line 5. The wheel 4 is knurled to provide a tractive engagement with the surface of the pipe and the other end of the frame is supported by a wheel 7 similarly carried on the frame. Extending downwardly on each side of the frame are the pivotally mounted arms 8, each of which is provided with a roller 9 at the lower end adapted to engage the side of the pipe. Each of the arms 8 is provided with an arm 11 extending upwardly past the pivotal connection 12, and having a link 13 on the end thereof extending thru the side of the frame and provided with a nut 14 between which and the frame is interposed a spring 16. Thus the rollers 9 are resiliently held against the 25 side of the pipe to maintain the frame in upright position about the pipe. It is desirable also to have a workman alongside of the machine to ensure its proper position during operation, as the nature of the ground over which such a machine must operate is usually such as to preclude the use of mechanism for keeping the machine upright and operating from the surface of the ground.

Fixed on the shaft 3 is a gear 18 in mesh with 35 a gear 19 having clutch element 21 fixed thereon and journaled on the shaft 22 journaled in the frame 2. A clutch sleeve 23 splined upon the shaft 22 provides means for locking the gear 19 to the shaft 22 and this clutch sleeve is controlled by a lever 24 pivoted upon a fixed arm 26 extending from the frame of the machine.

The shaft 22 is also provided with a fixed sprocket 31, connected by the chain 32 with a sprocket on the jack shaft 33, connected by the 45 worm gearing 34 with the shaft of the reversible motor 36. The motor is mounted upon suitable cross-bars 37 arranged on the frame 2 and is controlled by the usual switch 38. Thus by engaging the clutch element 23 with the gear 19, the 50 frame may be moved in either direction along the pipe line.

Extending from the underside of the frame is a large bearing 41, having the bearing cap 42 held thereon by readily releasable means such 55

as the bolts 43. Journaled within this bearing and retained therein by the flange 44 is a cylindrical barrel or rotor 46 provided with the gear teeth 47 at one end adjacent the bearing and 5 extending beyond the bearing on the other side to a flange 48. Since the pipe line to be wrapped is already installed and usually in use, and since it is necessary that the barrel should surround the pipe line, the barrel is made in two pieces so 10 that it may be assembled around the pipe and then seated within its bearing. Preferably the barrel is made in two parts with suitable interlocking or dovetail devices 49 arranged in the end flanges. The flange 44 on the drum which 15 seats within a complementary groove in the bearing 41 prevents axial disengagement of the interlocking devices after assembly of the drum parts within the bearing.

Mesning with the teeth 47 is a gear 51 journaled upon the frame in a suitable bearing and connected for rotation to the shaft 22 by means of the beveled gears 52, so that with rotation of the drive shaft 22 the barrel 46 is rotated.

Journaled upon the projecting end of the barrel 25 is a spool or reel 53 preferably provided with a projecting flange 54 journaled within a complementary seat inside the bearing 41. The spool is also made in two parts dovetailed together by interlocking devices 56 arranged in the spool 30 flanges 57; and because of the mounting of the spool flange 54 within the bearing 41, axial disengagement of the assembled parts is prevented.

From the above it will be understood that by 35 a removal of the bearing cap 42 and rotation of the spool and drum to properly align the joints, the lower half of the spool may be laterally moved to the left (of Figure 2) to disengage it from the upper half and that the lower half of 40 the drum may then be similarly disengaged, thus permitting the machine to be lifted off of the pipe line. To apply the machine to a pipe line, the parts are assembled in the reverse order.

Carried in fixed position on the end of the barrel 45 46 is a wrapping arm 61, for applying the strip of wrapping material 62 from the spool to the pipe. The position of this arm must be very carefully adjusted and we provide a universal connection 63 on the end of the barrel for mounting the arm. Since it is desirable to exert tension upon the strip 62 in order to draw it tightly about the pipe, we provide a bar 64 parallel to the wrapping arm 61 and held thereagainst by the springs 66, the tension of which may be adjusted by the nuts 67, so that the desired degree of tension may be exerted by the wrapping arm 55 upon the wrapping strip.

The rotation of the barrel of course imparts to 60 the wrapping arm an orbital rotation about the pipe and with the movement of the frame along the pipe such orbital movement of the wrapping arm is in a spiral direction about the pipe.

The wrapping strip is taken from the spool 65 upon which it has been previously wound, and in order to ensure a fair delivery of the wrapping strip from the spool to the wrapping arm, we prefer to pass the strip over a transfer arm 71 also fixedly adjusted on the end of the barrel by the universal mounting 72. Because of the 70 extensive surface of the bearing between the spool and the barrel there will be a desired frictional resistance between the two so that a certain amount of tension is placed on the wrapping strip as it leaves the spool. It will be understood that 75 the spool is not driven but that with the rotation

of the wrapping arm, it turns under the pull of the wrapping strip as the strip is wound upon the pipe.

Because the spool will hold but a relatively short length of the wrapping material, it is necessary from time to time, as the wrapping proceeds, to renew the supply of wrapping material on the spool. We therefore provide a spring-pressed lock 73 for connecting the spool for rotation with the barrel. A supply roll 74 of wrapping material is conveniently mounted upon the standards 76 fixed on the frame 2 and the end of the strip started on the spool by hand. By releasing the clutch sleeve 23, the motor may then be started to rotate the barrel and spool together 10 to fill the spool with wrapping material. When full the strip is torn and the torn end of the part on the spool led over the transfer arm 71 thru the wrapping arm and applied to the pipe, whereupon the wrapping operation may be continued. 15

Means are provided for applying a fluid between the pipe and the wrapping material. Preferably this fluid is of a bituminous nature such as asphalt of suitable grade and heated to give it fluidity. Of course the asphalt may be applied to the pipe or to the wrapping material, or to both and in our drawings we have shown two methods of applying it. Any cementitious fluid may be used but we prefer asphalt because it is highly resistant to decay, is water and acid proof and is extremely durable under the conditions to which it is exposed when buried in the earth. 20

25 Referring first to Figure 2, we have shown a tank 77 heated by the burner 78 and provided with a discharge pipe 79 controlled by the valve 81. The end of the pipe is disposed so as to discharge the fluid asphalt upon the pipe within the barrel and just ahead of the wrapping strip. The fluid so discharged is smeared over the surface of the pipe by means of the wipers 82 disposed spirally on the inside surface of the barrel so as to spread the fluid evenly over the surface 30 of the pipe and toward the wrapping strip.

35 In Figure 4 is shown an alternative means for applying the hot fluid. The barrel is provided with an annular passage 86 and a pipe 87 from the tank 77 is connected into the bearing 41 opposite this annular passage so that fluid flowing thru the pipe 87 fills it. Fixed on the inside of 40 this barrel and connected into this passage is a pipe 88 closed at the end and having a slot 89 for the delivery of a thin flat jet of the fluid. The length of the pipe 88 and the position of the slot 45 therein is such that the jet of fluid is delivered directly between the pipe and the wrapping strip 50 immediately before its contact with the pipe. A drain plug 90 permits the fluid in the passage to be drained out prior to the removal of the bearing when the barrel is disassembled. The quantity of fluid applied in either case is regulated 55 to an amount sufficient to thoroughly cover the pipe and seal the lapped joints between the edges of the strip.

We claim:

1. A pipe wrapping machine comprising a frame, a barrel adapted to surround the pipe and journaled on the frame, a spool journaled on the barrel, a releasable lock for connecting the spool for rotation with the barrel, and means for rotating the barrel. 70

2. A pipe wrapping machine comprising a frame, a spool for the wrapping material journaled on said frame and adapted to surround the pipe, a wrapping arm for applying the wrap- 75

- ping material and mounted on said frame for effect re-rolling thereon of sheet material from orbital rotation about the pipe, and means for a supply roll.
5. A pipe wrapping machine comprising a frame, means for supporting the frame for movement along the pipe to be wrapped, means for holding a roll of sheet wrapping material for movement with the frame, and means for rotating said holding means when desired to effect re-rolling thereon of sheet material from a supply roll. 5
3. A pipe wrapping machine comprising a frame, means on said frame for holding a roll 10 of sheet wrapping material from which the wrapping material is wound about the pipe and means for rotating said holding means when desired to
